Solomon B. Ellithorp. of New York, N.Y.
Letters Patent No. 1105. Dated June 7-1859.

The schedule referred to in these Letters Patent and making part of the same.

2

Des. 1105

To all whom it may concern:

It is known that I, Elizur W. Ellithorpe, of the city, county, and State of New York, have invented or produced a new and original design for a Sewing Machine, and do hereby declare that the following is a full and exact description of the same, reference being had to the accompanying Photographic impression, serving as a drawing of the same and making part of this Specification.

The purpose of the article shown in the drawing and the subject of the design is to contain the working parts of a Sewing Machine. It is a representation of a Squirrel in the attitude taken by that animal when feeding.

A duplicate part (reversed) of the one shown in the drawing, forms the completed figure when the two are put together, so as to show alike on both of its sides.

What I claim is the design for a Sewing Machine illustrated and shown in the accompanying drawing.
